UNITED STATES PATENT OFFICE.

LOUIS LEHR, OF BAYONNE, NEW JERSEY.

DESIGN FOR A BADGE, BUTTON, FINGER-RING, SCARF-PIN, OR SIMILAR ARTICLE.

50,995.

Specification for Design.

Patented July 3, 1917.

Application filed February 8, 1917. Serial No. 147,499. Term of patent 3½ years.

To all whom it may concern:

Be it known that I, LOUIS LEHR, a citizen of the United States, residing at No. 33 West 51st street, Bayonne, county of Hudson, and State of New Jersey, have invented a new, original, and ornamental Design for a Badge, Button, Finger-Ring, Scarf-Pin, or Similar Article, of which the following is a specification, reference being had to the

accompanying drawing, forming part thereof, which shows a badge illustrating by design.

I claim,

The ornamental design for a badge, button, finger-ring, scarf-pin, or similar article, as shown.

LOUIS LEHR.
